UNITED STATES PATENT OFFICE

96,806

DESIGN FOR A FENDER APRON

Gustave F. Bahr, Fairfield, Conn., assignor to Joseph H. Cohen, Bridgeport, Conn.

Application December 17, 1934, Serial No. 54,448

Term of patent 7 years

To all whom it may concern:

Be it known that I, Gustave F. Bahr, a citizen of the United States, residing at Fairfield, in the county of Fairfield and State of Connecticut, have invented a new, original, and ornamental Design for a Fender Apron, of which the following is a specification, reference being had to the accompanying drawing, forming part thereof.

The figure shows the obverse or face side of the fender apron, showing my new design.

The reverse side of the fender apron, not shown, is substantially plain and unornamented.

I claim:

The ornamental design for a fender apron, as shown and described.

GUSTAVE F. BAHR.
